UNITED STATES PATENT OFFICE.

GEORG ULLRICH, OF MAGDEBURG, GERMANY, ASSIGNOR, BY MESNE ASSIGNMENTS,
TO THE CHEMICAL FOUNDATION, INC., A CORPORATION OF DELAWARE.

MAGNETIC SEPARATOR.

1,366,979.

Specification of Letters Patent.

Patented Feb. 1, 1921.

Application filed January 21, 1916. Serial No. 73,374.

To all whom it may concern:

Be it known that I, GEORG ULLRICH, engineer, a subject of the German Emperor, residing at 2 Winterfeldtstrasse, Magdeburg, 5 Germany, have invented certain new and useful Improvements in Magnetic Separators, of which the following is a specification.

It is known in connection with magnetic separators to divide up the magnetic field into several zones which increase in strength in the direction of the stream of raw material under treatment, and to carry away the attracted material either conjointly or 15 separately according to its permeability. When this method is employed the magnet pole which is divided for the purpose of forming the zones is placed opposite a common or similarly divided counter magnet 20 pole, and the material is fed in and carried away through the gap in the field. The width of the gap in the field is therefore in this method not only dependent upon the magnetic properties of the material but it 25 must also in every case be greater than the size of the grains of the material. In this method the material will be attracted to one pole by the difference of the attractive forces of the two poles.

30 The present invention relates to a magnetic separator in which the magnetic field is likewise divided into several zones which increase or decrease in strength according to the construction in the direction of the 35 stream of the raw material, and in which as in the zone separators hitherto employed the attracted material is carried away either conjointly or separately. In contra-distinction however to the zone separators hitherto employed all the magnet poles are 40 situated in the present case on one side of the supply apparatus.

It is true that magnetic separators are already known in which all the magnet poles 45 lie on one side of the supply; in these separators however the zones, which cannot be regulated are of equal dimensions, with the object of forming a field of uniform 50 strength and as great a length as possible and causing the material attracted in the first field to fall as far away as possible from the non-magnetic material, a result which however is not obtained in practice. In any event these separators do not at all 55 act as zone separators.

According to this invention in contradistinction to the methods heretofore employed, the raw material is supplied in succession to the several zones lying on the same side of the material supply and each zone separates out a portion of the raw material. 60 The extraction of the magnetic material takes place in each zone so that the most efficient separation can be obtained. Furthermore, the zones can be regulated in respect 65 of their magnetic strength for the separation of raw material according to its permeability, whereby the zone fields can increase or decrease in magnetic strength in the direction of the supply of the raw material. 70 This regulation of the strength of the zone fields is effected in such case as may be desired, e. g. by mutual lateral adjustment of the pole shoes provided on the zone poles or by adjustment of the zone poles toward 75 the supply of the raw material. The lateral adjustment of the pole shoes or blades possesses the important advantage that the length of each zone can be regulated, a circumstance which enables the particular 80 magnetic zone to be allowed to act for a definite length of time on each kind of material. Again by adjusting the supply of the raw material in a direction toward the magnets the action of the latter on the material can be partially regulated. Furthermore the zone poles may be arranged so as 85 to swing for the purpose of regulating the field. Several or all of these methods of adjustment may be also employed in combination.

The distance apart of the coöperating pairs of poles is in the present separator only dependent upon the magnetic properties of the material and not also upon the 95 size of the grains of the material. Such a separator therefore may be used with advantage for coarse grained material. In such comparatively heavy bodies it is a special advantage of the new separator that the 100 coöperating poles act not with the difference but with the sum of their attractive forces. The separator may be also of the drum type as well as of the ring or of the traveling band type so that the discharge of the 105 attracted material may take place in the direction of the supply of the raw material as well as at right angles thereto.

In order that the said invention may be clearly understood and readily carried into 110

effect, the same will now be described more fully with reference to the accompanying drawings, in which:—

Figures 1, 2 and 3 are cross-sections showing alternative constructional forms of magnetic separators of the drum type embodying the invention.

Fig. 1^a shows a perspective view of apparatus illustrated in Fig. 1 taken on a line tangential to the delivery drum 7.

Fig. 4 shows a vertical section of a traveling-band type of separator;

Fig. 5 a vertical section of a multiple type of separator with circularly arranged fields;

Fig. 6 shows a similar section of a multiple separator with a two-zone field, four of such two-zone fields being arranged in a circle;

Fig. 6^a shows a plan view thereof;

Figs. 7 and 7^a show a modified form of Figs. 6 and 6^a in relatively similar views;

Fig. 8 a vertical section of a separator similar to Fig. 6, but without a specific delivery device;

Fig. 8^a shows a plan view thereof;

Fig. 8^b shows in plan view the lower rotatable pole shoe of Fig. 8 in somewhat modified form;

Figs. 8^c and 8^d show a multiple separator according to Fig. 8, in which provisions are made for partially or entirely eliminating the magnetic pull exerted upon the movable pole shoes.

Fig. 9 is a part elevation and part section of a separator with several working fields and

Fig. 10 is a view similar to Fig. 9 provided with a combined delivery and discharging device.

Referring first more particularly to Fig. 1, 1, 1', 2 and 3 denote the zone poles, the poles 1, 1' being excited by the coils 4. The excitation however may be effected differently, *e. g.* it may be effected by one coil only on one of the four poles, or by coils on the poles 3, 1'. The poles 1, 1' and 2 carry laterally adjustable shoes 5, by means of which the strength of the zone fields can be regulated. For the purpose of further regulation the pole 2 is arranged adjustably with respect to the supply of the raw material. The pole 3 is not adjustable. Furthermore, the entire magnet body can be rotated within the delivery drum 7 about the spindle 6, so that the raw material can be delivered not only at the point shown, but also in case of necessity at another point of the delivery drum.

The delivery drum may be made of magnetic or non-magnetic material.

In the present case the zone fields are arranged so as to increase in strength in the direction of the stream of raw material. The weakest zone 2—1' attracts only the most strongly magnetic portion of the ma-

terial supplied to the chute 8. Upon the chute is then deposited in the zone 1'—3 the feebly magnetic material and upon the chute is deposited in the strongest zone 3—1 the more feebly magnetic material. The delivery of the material is effected in the following manner:—The non-magnetic material is delivered at 9, the feebly magnetic material at 10 and 11 and the strongly magnetic material at 12. The pole shoes are with advantage provided with blades which lie in the direction of rotation of the drum 7 for the purpose of increasing the lines of magnetic force therein. It will be apparent that the distance between the pole shoes bears no relationship to the size of the grains of the material. The distance between the pole shoes is dependent only on the magnetic properties of the material.

In the form shown in Fig. 2 there are two zone fields and three poles 13, 14 and 15 are employed, the poles 13 and 15 being adjustable laterally and vertically and the pole 14 being only adjustable vertically. The field between the poles 13 and 15 is weaker than the field between the poles 13 and 14, so that strongly magnetic material is attracted under the pole 15 and feebly magnetic material under the pole 14. The delivery of the material is so effected that the non-magnetic portion emerges at 9 while the discharge of the feebly magnetic portion takes place at 10 and the strongly magnetic portion at 12.

In the form shown in Fig. 3 two zone fields are formed by poles 17, 18 and poles 16, 17, the poles 16 and 18 being provided with laterally adjustable pole shoes 5. The weaker field is produced between the poles 17 and 18.

In the traveling band type of separator shown in Fig. 4, four zone fields are provided in which for example the pole 19 is adjustable laterally and vertically and the pole 20 is only adjustable laterally, while members constituting the pole 21 are pivotally mounted. The supply of the material takes place in the direction of the arrow by means of an endless band 23 passing over guide rollers 22, the non-magnetic material being discharged at the right hand end of the band. The conveyance of the magnetic varieties of the material is effected by a delivery belt 24 which runs at right angles to the band 23 and can be divided up so as to constitute several belts, which, if necessary, may run at different speeds dependent on the amount of material to be conveyed.

In the adaptation to a separator of the multiple type shown in Fig. 5, there are arranged in a circle in a manner similar to that shown in Fig. 6^a four fields which are divided up each into zones each field being fed with material from the chute 8 and served by a common delivery device com-

prising a rotatable disk 25. In Fig. 5 only one of the four fields is shown. The poles 26, 27, 28 and 29 carry laterally adjustable pole shoes, the pole 26 being adjustable also vertically for the purpose of further regulation of the field.

In the form shown in Figs. 6 and 6^a four magnetic fields of two zones each are arranged in a circle. There is provided a pole 29 which is capable of being excited and carries a laterally adjustable shoe 5. Poles 30, 31, are also provided, which poles are vertically adjustable. A zone field is formed between the poles 31, 29 and between the poles 30, 29, respectively, so that the strongly magnetic material is attracted beneath the pole 31 and the feebly magnetic material attracted between the poles 30 and 29, the material thus attracted being carried away by the rotatable disk 25.

The form shown in Figs. 7 and 7^a is substantially the same as that described with reference to Fig. 6 except that each field is not excited separately. In the form shown in Fig. 7 all the fields which are arranged in a circle, are excited by a common axially disposed coil 32 and only one main pole 29 is provided, which carries a number of laterally adjustable shoes 5 corresponding to the number of the principal fields, (in this case four,) while each principal field is provided, as above described, with two vertically adjustable poles 30, 31.

The form shown in Figs. 8, 8^a, 8^b, 8^c, 8^d differs from that previously described particularly by the absence in this Fig. 8 of a separate delivery device. As shown in Figs. 8 and 8^a, vertically adjustable pole shoes 35 disposed beneath the poles 32, 33 and 34 are made in the form of rings which provide at the same time for the removal of the separated material. These rings are connected to the rotatable disk 36 composed partially of non-magnetic material. The poles 32 and 34 are adjustable vertically for the purpose of regulating the intensity of the zones. The regulation can be effected by this means alone or by adjustment of the aforesaid rings, or by adjustment of the rings and the poles 32, 34.

The polarity of the fields arranged in a circle may be uniform or alternate. In the former case which is illustrated in Figs. 8 and 8^a the lines of force run in a radial direction only. If on the other hand the four main fields have alternate polarity so that for example the outer pole 32 in one main field is a south pole but in the adjoining main field is a north pole as shown in plan view in Fig. 8^b, lines of force pass also from each pole of each field into the corresponding ring along to the poles of the adjoining fields corresponding to this ring. In this case it is advisable, not to make the rings 35 in one piece, but to make them of separate

magnetic pieces 35, which are separated from each other by air gaps or non-magnetic material 35^a. Corresponding small partial fields are thus formed which, as soon as the particular point emerges from a principal field, rapidly lose their magnetism so far that they easily throw off the attracted material. In the arrangement shown the force of the magnets directed upon the rings acts upwardly. In order partially or wholly to eliminate this force the magnet poles 32, 33 and 34 may also be of such a form that they do not act upon the upper horizontal surfaces of the rings 35 but upon their vertical side faces. How this is accomplished is shown for instance in Figs. 8^c and 8^d. In Fig. 8^c the outermost and innermost ring 35 are each arranged inside of the poles 32 and 34 respectively of each main field so that the magnetic paths extend in the direction shown in dotted lines. This relieves the magnetic upward pull on these two rings. If it be desired to also relieve the upward pull on the middle rings 35, the rings may be arranged with respect to their co-operative poles as shown in Fig. 8^d.

The form shown in Fig. 9 is provided with several main working fields of which only one is shown in the drawing and with a delivery drum 38 adapted to rotate about a vertical axis. Each principal field consists of two zones which are formed by the poles 39, 40 and 41 which are provided with adjustable pole shoes. The pole 41 is excited by the coil 4.

In the form shown in Fig. 10 a delivery and discharging device 42 of conical formation is adapted to rotate relatively to the magnetic fields which in general are produced and regulated in the same manner as that described with reference to Fig. 9. In the magnetic separators which deal with freely falling material this may be effected in the following manner: Of the whole of the magnetic material attracted in the first and strongest zone, only the strongly magnetic material, immediately it has fallen through the first zone and has passed into the weaker zone, is deflected thereby out of its path of descent while the action upon the feebly magnetic material is no longer sufficiently powerful to deflect it. In this manner therefore the two grades of magnetic material fall separated from each other and may thus be collected separately.

Having now particularly described and ascertained the nature of my said invention and in what manner the same is to be performed, I declare that what I claim is:

1. In a magnetic separator of the character described, an electromagnet having a plurality of pole pieces forming a plurality of magnetic zones of different intensity, all of said zones extending in one direction, means for feeding the material to be sepa-

rated in the direction in which the several zones extend, all of said zones being located on one side of said feeding means.

2. In a magnetic separator of the character described, an electromagnet having a plurality of pole pieces forming a plurality of magnetic zones of different intensity, all of said zones extending in one direction, means for feeding the material to be separated in the direction in which the several zones extend, all of said zones being located on one side of said feeding means, and means for adjusting the extent of each zone and the relative intensity between the zones.
3. In a magnetic separator of the character described, an electromagnet having a plurality of pole pieces forming a plurality of magnetic zones of different intensity, all of said zones extending in one direction, means for feeding the material to be separated in the direction in which the several zones extend, all of said zones being located on one side of said feeding means, said pole pieces being adjustable relatively to each other to vary the extent of each zone and the relative intensity between the zones.

4. In a magnetic separator of the character described, a plurality of electromagnets arranged in a circle, each electromagnet having a plurality of pole pieces forming a plurality of magnetic zones of different intensity, all of said zones extending in substantially radial direction in the circle in which the electromagnets are arranged, ring shaped concentrically arranged pole elements, all corresponding pole pieces of said electromagnets having one of said rings in common, said rings being suitably disposed with relation to said magnets, so that said zones of different intensity are formed between said rings, means for feeding the material, to be separated, beneath said rings in radial direction past the different zones, and means for varying the relative intensity between the different zones.

In testimony whereof the foregoing specification is signed in the presence of two witnesses.

GEORG ULLRICH.
